US00D972837S

(12) **United States Design Patent** (10) **Patent No.:** **US D972,837 S**
(45) **Date of Patent:** **** Dec. 20, 2022**

(54) **BACKPACK**

(71) Applicant: **Aer Designs LLC**, Union City, CA (US)

(72) Inventor: **Allen Choi**, Fremont, CA (US)

(73) Assignee: **Aer Designs LLC**, Union City, CA (US)

(**) Term: **15 Years**

(21) Appl. No.: **29/773,438**

(22) Filed: **Mar. 9, 2021**

(51) LOC (13) Cl. **03-01**

(52) U.S. Cl.

USPC **D3/216**

(58) **Field of Classification Search**

USPC D3/214–226, 230–233, 242–244, 254
CPC A45F 3/00; A45F 3/005; A45F 3/02; A45F 3/04; A45F 3/042; A45F 3/047; A45F 3/06; A45F 3/08; A45F 3/10; A45F 2003/001; A45F 2003/002; A45F 2003/003; A45F 2003/006; A45F 2003/007; A45F 2003/008; A45F 2003/025; A45F 2003/045; A45F 2200/00; A45F 2200/05; A45F 2200/0525; A45F 2200/0533

(57) **CLAIM**

The ornamental design for a backpack, as shown and described.

DESCRIPTION

FIG. 1 is a rear, left, and top perspective view of a backpack showing the new design;

FIG. 2 is a rear view thereof;

FIG. 3 is a front view thereof;

FIG. 4 is a bottom view thereof;

FIG. 5 is a top view thereof;

FIG. 6 is a right view thereof; and,

FIG. 7 is a left view thereof.

The broken lines showing zipper structures depict portions of the backpack that form no part of the claimed design.

1 Claim, 3 Drawing Sheets
